UNITED STATES PATENT OFFICE.

FRANK M. HILL, OF CAMDEN, NEW JERSEY.

ICE BOX FOR USE AT SODA FOUNTAINS.

Application filed December 3, 1921. Serial No. 518,712.

To all whom it may concern:

Be it known that I, FRANK M. HILL, a citizen of the United States, residing at Camden, in the county of Camden and State of New Jersey, have invented new and useful Improvements in Ice Boxes for use at Soda Fountains, of which the following is a specification.

This invention relates to ice boxes, cabinets, refrigerators and the like and it has more particular reference to soda fountain ice cabinets, the primary object being to provide a novel means whereby such cabinets are rendered effective in action in so far as cold energy conservation and restoration are concerned. More specifically defined the fundamental characteristic of my present invention resides in the provision of a novel means whereby the prevailing loss of cold energy due to the constant opening and closing of such cabinets as are above referred to is effectively prevented whereby considerable economy in ice and brine consumption is effected and the efficiency thereof is correspondingly increased.

Another object of this invention is to eliminate to a great extent the frequent recharging of refrigerator cabinets of the kind referred to with fresh ice and brine by furnishing an auxiliary ice storage chamber in connection therewith from which the ice water and salt solution is fed into the brine tank proper as required.

A further object aimed at by the present invention is a novel means whereby ice cream cans, containers and the like are supported in relation to the refrigerating mixture whereby their contents are maintained at a uniform degree of refrigeration, whilst said cans, containers and the like are prevented from fouling or interfering with each other when the cabinet lid or cover is raised.

A still further object had in view by my present invention is to uniformly distribute the cold energy evenly all about the refrigerator cabinet or chamber proper.

A yet further object of my invention is to provide a novel means whereby the overflow level in ice cream boxes, cabinets, refrigerators and the like can be regulated relative to the top of the ice cream cans whereby the ingress of ice and brine thereinto is positively prevented.

With the foregoing and other objects in view as will be more apparent from the following description, my present invention

primarily consists essentially in the combination with a refrigerator brine tank of a supplementary ice and salt storage receptacle or chamber from which cold energy is supplied and evenly distributed throughout the aforesaid brine tank. A secondary characteristic of this invention is the provision of a regulatable overflow whereby the level of the brine and ice solution can be easily controlled and varied.

In the further disclosure of the invention reference is to be had to the accompanying sheet of explanatory drawings constituting a part of this specification, and in which like characters of reference designate the same or corresponding parts in all the views.

Figure 1—is a longitudinal vertical section through an ice-box for soda fountain usage and embodying one practical embodiment of my present invention.

Figure 2—is a top plan view of the same with the covers removed.

Figure 3—is a fragmentary sectional elevation of a slightly modified form of the invention.

Figure 4—is a perspective view of a detail hereinafter more particularly referred to; and,

Figure 5—is a detail of the overflow controlling and varying means.

Referring more particularly to the views the numeral 5 designates a refrigerator for soda fountain usage more particularly and including inner and outer spaced walls, 6, 7 respectively between which are appropriate insulation 8, the ordinary cover being indicated by the reference character 9. At an appropriate distance from one end of the refrigerator 5 I insert, fit in or build a partition 10 of like character to the walls thereof whereby said refrigerator is divided into a brine tank proper 11 and an ice-storage chamber 12, communication between the two being established by means of an inverted channel section or trough 13 substantially closed in at 14 and having an aperture 15 for a purpose later on explained. This inverted channel section or trough 13 is of suitable length so that the aperture 15 therein is located centrally of the brine tank 11. Arranged to seat on, or it may be made an integral part of, the ice storage chamber 12 is an upstanding extension 16—the walls whereof correspond in structure to the walls of the refrigerator 5, and said extension is closable by means of a removable cover 17

as will be clearly understood from Figure 1; or, said cover 17 may serve to close the top of the ice storage chamber 12 when it is not extended upwards as shown but is on a 5 level with the top of the refrigerator.

Supported or seated on an appropriate stand or footpiece 18 in the lower part of the ice-storage chamber 12 is a tray or receptacle 19 for a quantity of salt 20 on which 10 the broken ice 21 is stacked until said chamber 12 and extension 16 are filled. Arranged in a convenient position within the brine tank 11 is the stand-pipe or overflow 22, which is extended down through the bottom 15 of the refrigerator and elbowed at 23 to a substantially horizontal pipe 24 having a T 25 at its other end from which a branch pipe 26 is extended down into a suitable settling tank, barrel or the like 27 in the cellar 20 or basement, said branch pipe 26 having fitted therein an appropriate shut-off valve or stop cock 28 for a purpose later on explained. Extended upwards from the aforesaid T 25 is a pipe 29 connected into the 25 suction end or inlet 30 of an appropriate circulating pump 31, and from the outlet or discharge 32 of said pump 31 is an inverted U-shaped pipe 33 elbowed at 34 and extended into an appropriate union 35, that 30 constitutes a coupling for a pipe 36 concentric with and of larger diameter than the aforementioned stand-pipe or overflow 22. At the upper end of the pipe 36 and within the brine tank 11 is a transversely disposed 35 union 37 from which is branched a pipe 38 extending substantially along the floor or inner bottom of the refrigerator 5 through the inverted trough or channel 13 and ice-storage chamber 12, its free end being fitted 40 with an elbow 39 from which projects vertically upwards a pipe 40 having a branch 41 at its upper end terminating in a nozzle or outlet 42 axially central of the upper part of the said ice-storage chamber 12.

45 In order to provide an effective and reliable support for the ice-cream cans or other receptacles 43 when immersed in the solution within the brine tank 11 I preferably employ a false or inner cover 44 appropriately supported on a surrounding flange 45, the apertures in said cover 44 having expandible ring flanges 46 which serve to maintain the cans 43 perfectly vertical, said expandible ring flanges 46 being employed to 50 accommodate structural inequalities in said cans. It is also to be observed that the cans or other receptacles 43 are supported or suspended within the brine tank 11 by the usual bead or lip 47 at or near their upper 55 edge whereby the ordinary covers 48 therefor can be freely removed and replaced. Still further it is to be noted that the cans or other receptacles 43 are suspended from the false or inner cover 44 so that they are 60 completely surrounded by the brine solution

at a level so as not to contact with or foul either the channel or trough 13, pipe 38 or stand-pipe 22. Thus it will be readily seen and very clearly understood that when the ordinary cover or lid 9 is raised comparatively little or no cold energy can escape save that which is liberated when the cover of any one individual can or other receptacle 43 is removed to take ice cream therefrom or for replenishing purposes. 70

In the modified form of the invention shown in Figure 3 it is to be observed that the ice-chamber 16^a is made as a detached unit and is connected up to the refrigerator by means of a coupling 49 through which 80 the pipe 38 is axially conducted so that a supporting passage is provided for the flow of the solution from said chamber into the brine tank 11 as will be readily understood by those acquainted with the art to which 85 this invention appertains.

Still further I wish to point out that in the form of the invention illustrated by Figures 1 and 2 the dividing wall between the brine tank 11 and ice-storage chamber 12 90 may be constructed as a vertically movable slide so that whenever desired broken ice may be allowed to flow into the brine-tank 11.

In order to provide a simple and effective means for regulating or varying the overflow level of the brine solution in the brine tank 11 I employ the means illustrated by Figure 5 and which consists in fitting an adjustable sleeve or coupling 50 on the upper end of the stand pipe 22, the upper part 51 of said sleeve 50 being fashioned slightly funnel-shaped or upwardly and outwardly flared to constitute a friction seat for the correspondingly tapered lower end of a tubular nipple 52. It will of course be readily seen that when the nipple 52 is frictionally seated in the upper part of the sleeve or coupling that the height of the stand-pipe 22 will be raised with the consequential raising of the overflow level of 110 the waste brine solution. Obviously two or more such nipples 52 may be provided to give varying overflow levels as will be readily comprehended by those acquainted with the art to which my invention appertains. 115

From the foregoing description and an examination of the drawings it will be apparent that by my present invention there is provided what may be termed a refrigerator 120 with which is associated a circulating system whereby the less dense or warmer solution passing to waste or overflowing may be circulated back through the refrigerator into the ice-storage chamber 12 and thereby 125 caused to become recharged with cold energy before re-entering the brine tank 11. In use the valve or stop cock 28 will be kept open whereby the warmer or gradually rising upper strata or surface of weakened brine solu- 130

tion will flow down the pipes 22, 24 to the settling tank or barrel 27, from which it can be circulated by the pump 31 through the pipes 33, 36, 38, 40, 41 to the top of the ice-storage chamber 16 from which it will flow back into the brine tank 11 as hereinbefore set forth and described. On the other hand by closing the valve or stop cock 28 the content of the entire brine tank 11 may be circulated through the ice-storage chamber 16 and fully recharged with highly concentrated cold energy as will be perfectly obvious without further explanation or description.

Whilst these has been shown and described practical embodiments or specific applications of my present invention it will be perfectly clear that the same is susceptible of variation and modification, and the right is hereby reserved to make such changes or modifications therein as fairly lie within the scope of the appended claims.

Having described my invention, what I claim as new and desire to secure by Letters Patent is:

1. A refrigerator, comprising a brine tank, a chamber adjacent thereto for ice and salt, a duct for establishing communication between the lower portions of the tank and

chamber, said duct opening into the brine tank at its lower central portion, a pipe extending through the duct and discharging into the upper portion of the ice chamber, and means for forcibly circulating fluid through said pipe, downwardly through the upper portion of the ice chamber, the fluid passing thence through the duct, into the lower portion of the brine tank.

2. A refrigerator, comprising a brine tank, a chamber adjacent thereto for ice and salt, an inverted channel member supported on the bottom of the tank and bottom of the chamber and establishing communication between the tank and chamber, a pipe extending through the channel member and discharging into the upper portion of the ice chamber, means for forcibly circulating fluid through said pipe, downwardly through the upper portion of the ice chamber, the fluid passing thence through the channel member into the lower portion of the brine tank, and means for withdrawing the upper warmer portion of the solution in the brine tank and conveying it to the means producing circulation.

In testimony whereof I affix my signature.

FRANK M. HILL.
